BRASSIÈRE

Ernestine P. Ries, Delray Beach, Fla.

Application June 9, 1948, Serial No. 31,929

1 Claim. (Cl. 2—42)

1

This invention relates to an improvement in brassières, or as commonly known, bra.

It is an object of the invention to provide a bra constructed for adequate support of the breasts by a simple cord or neck band, together with wrap around waist bands, thus eliminating the undesirable shoulder straps commonly employed.

A further object of the invention resides in the improved bra formed with cup supports for the breast and having supporting tapes or bands so arranged and connected as to cause the cups to snugly embrace the breasts by the simple expediency of a neck cord or supporting member and wrap around extended ends to the tapes.

Another object resides in the particular manner of attachment of the tapes for presenting the maximum support of the bra to the contour of the body of the user, preventing shifting or distortion of the bra in use.

Another object is the extreme simplicity of the bra, embodying the very desirable features of a backless bra, with the only supporting means being a very inconspicuous cord about the neck, yet presenting a snug fitting garment amply supported and secured about the waist of the user.

Other important objects of the invention will readily present themselves during the course of the following description, reference being had to the accompanying drawings, wherein is illustrated a preferred embodiment of the invention.

In the drawings;

Figure 1 is a perspective view of a bra constructed in accordance with the invention and in use, and

Figure 2 is a front elevation of the bra in extended position.

Referring specifically to the drawings, the numeral 5 designates the bra as a whole, embodying cupped portions 6, preferably formed of a single piece of material, although obviously the device may be fabricated from a number of pieces. The cups are caused to maintain their contour by any convenient means, such as wire reinforcing, indicated generally in dotted lines at 7. The cups and the surrounding material assumes a generally wedge shape and terminate upwardly in points 8 and 9. The lower portion of the bra is preferably formed straight and a connecting section of webbed resilient material is fitted therein, secured to the area of material surrounding the cups, as shown at 10.

Non-elastic supporting tapes 11 and 12 are stitched to the bra in diagonally disposed relation, crossing each other at approximately a

2

point 13 and passing under the cups 6 in opposite directions, following generally the curvature of the cups. The tapes are extended beyond the terminal ends of the bra and are adapted in use to be wrapped about the waist of the user in opposite directions, terminating at the front of the user, where they are secured together in any convenient manner, such as by snap or hook fasteners. The tapes firmly support the bra in close contact to the breasts and body of the user. The tape 11 is extended upwardly, as at 15, to be passed about the neck, as shown in Figure 1, and is provided with a snap or hook fastener at its free end, as at 16, to engage a companion fastener at the point 9 of the bra. However, the extended end 15 may be dispensed with and a relatively thin inconspicuous cord substituted therefore, fixed at the point 8 and either provided with a separable fastener at its opposite end or permanently fixed at the point 9. The tape or cord 15 forms a loop to be supported upon the neck and serves as a vertical support for the bra, transmitting its supporting pull through the tapes 11 and 12 for providing a lifting action to the cups 6, maintaining a firm support of the breasts.

Side tapes 17, either elastic or non-elastic are stitched along the outer ends of the bra and generally follow the contour of the cups. The tapes 17 extend from the points 8 and 9 and terminate at the lower terminal points of the bra, as at 18. The tapes provide a supporting medium substantially throughout the area of the cups, causing the cups to snugly embrace the breasts and prevent sagging or wrinkling by the constant upward force exerted by the neck cord 15.

While the tapes 11 and 12 have been described as being non-elastic, it will be obvious, that these tapes could be formed of an elastic material and, in certain instances, it becomes desirable that elastic be employed, since the waist encircling ends will permit various body movements, while at the same time maintaining a snug engagement of the bra.

In use, the cord is placed about the neck and the cups engaged over the breasts snugly. The bra is then drawn down closely to the body and the tapes 11 and 12 passed about the waist in opposite directions and brought around to the front, where they are secured together by the fastener 14. The elastic webbing 10 firmly engages the body and permits the cups to more evenly adjust themselves to the breasts. Throughout the use of the bra, the continued

upward pull of the cord 15 upon the tapes 11, 12 and 17, maintains a constant restricting force to the tapes to continually snugly embrace the breasts.

It will be seen from the foregoing that a very desirable and highly efficient bra has been provided. The conventional objectionable shoulder straps have been eliminated, making the bra particularly adaptable for formal dress, while the cord about the neck provides adequate support and may be made of any inconspicuous material. The bra is simple in construction, strong, durable, cheap to manufacture and is extremely practical as a snug fitting garment supported in a most novel manner.

It is to be understood, that the invention is not limited to the precise arrangement shown, but that it includes within its purview, whatever changes fairly come within either the terms or the spirit of the appended claim.

Having described my invention, what I claim is:

A bra of the character described formed of a pair of wedge shaped sections of textile material spaced apart and united by an elastic webbing, the wedge shaped sections arranged with their apexes upward, a preformed reinforced breast supporting cup carried by each section substantially centrally thereof and in vertical alignment with the apexes, tapes stitched to the wedge shaped sections beginning at the apexes and passing downwardly in opposite directions to cross at an approximate horizontal center line

5 10 15

of the cups and passing beneath the cups, said tapes stitched throughout the area of the wedge shaped sections and extended beyond the outer lower extremities of the wedge shaped sections to form body encircling ties, a second pair of tapes stitched to the outer marginal edges of the wedge shaped sections starting at the apexes and extending over and around the cups and united with the first named tapes at the outer lower extremity of the wedge shaped sections, a neck encircling cord permanently connected to the apex of one wedge shaped section and carrying a separable fastener element at its free end and a separable fastener element carried by the apex 15 of the opposite wedge shaped section.
